UNITED STATES PATENT OFFICE.

ALFONS VAN ROSSUM, OF FRANKFORT-ON-THE-MAIN ESCHERSHEIM, GERMANY.

FIREPROOF RECEPTACLE FOR FILMS AND OTHER COMBUSTIBLE MATERIALS.

Application filed October 20, 1926, Serial No. 142,988, and in Germany October 27, 1925.

This invention relates to fireproof receptacles for films or other combustible materials having several compartments which are closed by a single door.

5 An object of the present invention is to provide an improved receptacle wherein the closure therefor is so constructed that ingress of fire into any of its compartments, either from the exterior of the receptacle 10 or from an adjacent compartment, is effectively minimized.

Another object is to provide a door for the several compartments of the receptacle which embodies a single closure common to 15 all of the compartments, and an individual closure for each compartment with means on the single closure constituting a wall which will prevent fire from passing between adjacent compartments.

20 The above and other objects will appear more clearly from the following detailed description, when taken in connection with the accompanying drawing, which illustrates a preferred embodiment of the inventive 25 idea.

In the drawings, hereto attached, forming a part of the specification, Figure 1 is a vertical longitudinal section of the whole receptacle, Figure 2 is an enlarged vertical 30 longitudinal section of the middle part of the receptacle and door and Figure 3 shows the same but with the door bent by fire.

The receptacle 1 of the present invention is shown as provided with compartments A 35 and B for the reception of films and other combustible materials, it being understood that as many of these compartments may be provided as is found convenient. The compartments A and B are separated by the 40 horizontal wall 2 and are closed by a single door 3 common to said compartments, and the frame 4' of which fits into the recessed portions of the outside walls 5 of the receptacle. An individual inner closure 45 6 is provided for each compartment and connected to the common closure 3 by studs 7 extending inwardly from the inner wall 4 of the latter closure. The individual closures 6 are provided with apertures 8, while the double inner and outer walls of the common closure 3 are formed with apertures 9 and 10, respectively, offset relative to each other and to the apertures 8. These various apertures in the closure members form channels for the escape of gases from the 50 compartments, as indicated by the arrows in

Figure 1. The apertures 8 and 10 are closed by screens 11, which prevent the escape of flames from the compartments and at the same time permit the gases to flow 60 therefrom.

The outer edge of the wall or partition 2 is provided with a groove containing a filler 17 and said groove is opposed to a like groove in the stile 16 of the closure 3 in 65 which is disposed a filler 18. The innermost wall 4 of the closure 3 is formed with the oppositely extending perpendicular flanges 12 and 13 which project, respectively, into the grooves in the partition 2 and the stile 70 16 and combine to provide a horizontally extending fire wall which prevents the passage of fire from one compartment into an adjacent one.

As shown in Figure 3, should the outer 75 walls of the closure 3 become warped, due to heat from the exterior of the receptacle, the inner wall 4 and the flange 12 will still have a tendency to remain in their normal positions and thereby effectively close communication between the adjacent compartments A and B.

I am aware that various alternations and modifications of this device are possible without departing from the spirit of my 85 invention, and I do not therefore desire to limit myself to the exact form of construction and arrangement shown and described.

I claim as new and desire to secure by Letters Patent:—

90 1. A receptacle for combustible materials including a plurality of compartments with a dividing wall therebetween, a door for the receptacle including an outer closure common to said compartments, a fire wall 95 on said outer closure recessed within said dividing wall when the closure is in closing position, and an inner closure for each compartment carried by said outer closure.

100 2. A receptacle for combustible materials including a plurality of compartments, a door for the receptacle including an outer closure common to said compartments, and an inner closure for each compartment carried by said outer closure, said outer and 105 inner closures having apertures therein offset relative to each other.

110 3. A receptacle for combustible materials having an intermediate partition dividing the same into compartments, a door for the receptacle including an outer closure common to said compartments and an inner clo-

sure for each compartment carried by said outer closure, and a flange on said outer closure projecting into a groove formed in said partition and constituting a fire wall 5 between said compartments.

4. A receptacle for combustible materials having an inner intermediate partition dividing the same into compartments and formed with a groove therein, a door for the 10 receptacle including an outer closure common to said compartments and having a stile provided with a groove therein, and also having an inner wall provided with oppositely extending flanges projecting into the 15 grooves in said partition and stile and constituting a fire wall between said compartments, and inner closures carried by said outer closure and each individual to one of said compartments.

5. A receptacle for combustible materials 20 having an inner intermediate partition dividing the same into compartments and formed with a groove therein, a door for the receptacle including an outer closure common to said compartments and having a stile 25 provided with a groove therein, and also having an inner wall provided with oppositely extending flanges projecting into the grooves in said partition and stile and constituting a fire wall between said compartments, inner closures carried by said outer closure and each individual to one of 30 said compartments, and a filler in each of said grooves engageable by the flanges projecting into the grooves.

In testimony whereof I have affixed my signature.

ALFONS VAN ROSSUM.
